US00D509205S

(12) **United States Design Patent** (10) Patent No.: **US D509,205 S**
Lodato et al. (45) Date of Patent: **** Sep. 6, 2005**

(54) **HOUSING FOR A COMMUNICATION DEVICE**

(75) Inventors: **Franco Lodato**, Weston, FL (US); **Matthew R. Michieli**, Gilbert, AZ (US); **James Isbell**, Phoenix, AZ (US); **Hartmut H. Esslinger**, Los Gatos, CA (US); **Howard Nuk**, Sunnyvale, CA (US); **James Whittaker**, Herrenberg, DE (US); **Carles Puche**, Herrenberg, DE (US); **Po Yi Ng**, San Jose, CA (US)

(73) Assignee: **Motorola, Inc.**, Schaumburg, IL (US)

(**) Term: **14 Years**

(21) Appl. No.: **29/212,304**

(22) Filed: **Aug. 30, 2004**

(57) CLAIM

The ornamental design for a housing for a communication device, as shown and described.

DESCRIPTION

FIG. 1 is an isometric view of a housing for a communication device showing our new design; FIG. 2 is a right side orthographic view thereof; FIG. 3 is a front orthographic view thereof; FIG. 4 is a left side orthographic view thereof; FIG. 5 is a rear orthographic view thereof; FIG. 6 is a top orthographic view thereof; and, FIG. 7 is a bottom orthographic view thereof.

The broken lines shown in FIGS. 1-7 represent environmental elements and form no part of the claimed design. The dotted lines shown in FIGS. 1-4 and FIGS. 6-7 represent an unclaimed border between claimed and unclaimed subject matter and form no part of the claimed design.
